(57) **CLAIM**

(21) Appl. No.: **29/274,398**

The ornamental design for a roof of a rotating laser having telescopic sight, as shown and described.

(22) Filed: **Apr. 20, 2007**

DESCRIPTION

(51) LOC (8) Cl. **10-04**

FIG. 1 is a front view of the roof of rotating laser;

(52) U.S. Cl. **D10/66; D10/69; D10/70**

FIG. 2 is a rear view of the roof of rotating laser;

(58) Field of Classification Search D10/66,

FIG. 3 is a left-side view of the roof of rotating laser;

D10/69, 70; 33/276, 277, 281, 285, 286,

FIG. 4 is a right-side view of the roof of rotating laser;

33/290, 291-299, DIG. 21; 340/573.1-573.4,

FIG. 5 is a plan view of the roof of rotating laser;

340/539, 825.36, 825.46, 825.49, 357.02,

FIG. 6 is a bottom view of the roof of rotating laser;

340/357.07-357.09; 356/5.15, 4.01, 5.01,

FIG. 7 is a plan view of the rotating laser having telescopic

356/4.05, 5.05-5.09, 5.12, 28.5, 345, 375,

sight; and,

356/3.01, 128-155, 399-400; 385/83, 97-99,

FIG. 8 is a perspective view of the rotating laser having

385/134-139; 701/211-213, 150, 158; 264/1.24-1.25

telescopic sight taken from front, right, upper direction.

See application file for complete search history.

The broken line showing of portions of a laser is included for the purpose of illustrating non-claimed subject matter and forms no part of the claimed design.
